US00D996627S

(12) **United States Design Patent** (10) **Patent No.:** **US D996,627 S**
(45) **Date of Patent:** **** Aug. 22, 2023**

(54) **MEDICAL COOLING DEVICE**

(71) Applicant: **RECENSMEDICAL, INC.**, Ulsan (KR)

(72) Inventors: **Gun Ho Kim**, Ulsan (KR); **Kyong Kwan Ro**, Uijeongbu-si (KR); **Boo Seong Park**, Hwaseong-si (KR); **Chul Ho Lee**, Yongin-si (KR); **Ho Young Joo**, Goyang-si (KR); **Eun Ho Kim**, Seoul (KR)

(73) Assignees: **RECENSMEDICAL, INC.**, Ulsan (KR); **UNIST (ULSAN NATIONAL INSTITUTE OF SCIENCE AND TECHNOLOGY)**, Ulsan (KR)

(**) Term: **15 Years**

(21) Appl. No.: **29/866,478**

(22) Filed: **Sep. 14, 2022**

Related U.S. Application Data

(63) Continuation of application No. 29/760,758, filed on Dec. 3, 2020, now Pat. No. Des. 968,627.

(51) **LOC (14) Cl.** **24-01**
(52) **U.S. Cl.** **USPC D24/200**

(57) CLAIM

The ornamental design for a medical cooling device, as shown and described.

DESCRIPTION

FIG. 1 is a perspective view of a medical cooling device according to the new design.

FIG. 2 is a front view of the medical cooling device of FIG. 1.

FIG. 3 is a rear view of the medical cooling device of FIG. 1.

FIG. 4 is a left side view of the medical cooling device of FIG. 1.

FIG. 5 is a right side view of the medical cooling device of FIG. 1.

FIG. 6 is a top plan view of the medical cooling device of FIG. 1; and,

FIG. 7 is a bottom plan view of the medical cooling device of FIG. 1.

The broken lines shown in figures illustrate portions of the medical cooling device that form no part of the claimed design.
